H. E. HERRICK

HOUSE NUMBERING DEVICE

Filed Mar. 30, 1922

By *Lester Sargent.*

Attorney

UNITED STATES PATENT OFFICE.

HENRY E. HERRICK, OF MINNEAPOLIS, MINNESOTA.

HOUSE-NUMBERING DEVICE.

Application filed March 30, 1922. Serial No. 548,153.

To all whom it may concern:

Be it known that I, HENRY E. HERRICK, a citizen of the United States, residing at Minneapolis, in the county of Hennepin and 5 State of Minnesota, have invented a new and useful House-Numbering Device, of which the following is a specification.

The object of my invention is to provide a novel illuminating house numbering device having a novel reflector and having a novel form of casing, and the improved combination and arrangement of parts hereinafter described and illustrated in the accompanying drawings, in which:—

15 Figure 1 is a perspective view of the invention shown in use;

Fig. 2 is a perspective view of the device by itself;

20 Fig. 3 is a cross section on line 3—3 of Fig. 2; and

Fig. 4 is a longitudinal section on line 4—4 of Fig. 3.

Like numerals indicate like parts in each of the several views.

25 Referring to the accompanying drawings, I provide a casing having a back 1 formed from a single strip of suitable material, preferably aluminum, and having a top 2, bottom 4 and top flange 3 and bottom flange

30 5. The bottom member 4 is of less width than the top member 2, so that the number on the device may be very readily viewed by a person on the street. I provide a suitable strip of glass 8, preferably clouded, on 35 which the desired number 9 is displayed. The glass 8 is held in place by the ends 7 of the curved reflector 6, the back of which abuts against the back portion 1 of the casing. I provide suitable blocks 10 engaging 40 against the ends of curved reflector 6, and I further provide suitable end casing covers 11 of the same material, preferably aluminum, as the main casing. Positioned centrally in the casing I provide a suitable 45 small electric lamp bulb 12 which may be supplied with current from any suitable

source of current. To open the device to replace a burned out electric lamp, one of the covers 11 which frictionally engages the casing is removed, as is also the adjacent 50 block 10. The glass 8 may then be withdrawn sufficiently to gain access to the lamp 12, and if found more convenient the reflector 6 may also be removed. The glass is not affixed to any part of the apparatus but is 55 merely held in place by frictional engagement with the flange portions of covers 11 and the ends 7 of reflector 6. Reflector 6 is a narrow rectangular longitudinally curved strip of suitable polished metal, preferably 60 aluminum, the principal parts of the device being of aluminum, which is of light weight. As the top 2 is of greater width than the bottom portion 4 the glass number plate 8 is mounted in a forwardly slanting position 65 which makes it convenient to read by a person on the sidewalk.

I also may use the device for displaying the name of a physician or other professional man, and the element 9 shall be construed to 70 apply to such a name if printed on the glass 8 in lieu of a house number, or to both if both are displayed on the glass in opaque lettering.

75 What I claim is:—

In a house numbering device, the combination of a metal casing having an open face, the top of said casing being of greater width than the bottom portion thereof, end casing covers suitably shaped to engage 80 with and removably mounted on the ends of the casing, a glass plate bearing a number mounted in the open face of the casing, a rectangular longitudinally curved reflector mounted in the casing and having its 85 central portion abutting against the back of the casing and having its ends abutting against the glass plate to hold same in place, and an electric lamp mounted midway of the interior of the casing.

HENRY E. HERRICK.
